NOVELTY CLOCK

Leon G. Livingston and Aldice O. Dinsdale, San Francisco, Calif.; said Dinsdale assignor to said Livingston

Application October 23, 1937, Serial No. 170,614

5 Claims.

(Cl. 58—2)

This invention relates to novelty clocks, and particularly to a clock designed to attract attention by normally acting in an eccentric manner and by showing the correct time of day only 5 at certain times.

It is the object of the invention to provide a clock having the usual face and hands, with means for moving the hands with no reference to the time of day, and with other means to control 10 the movement of the hands, or to stop the hands at a position with respect to the face to indicate the exact time in the conventional manner.

This and other objects which will appear from an understanding of the following specification 15 and accompanying drawings are accomplished by the provision of a normally operating clock mechanism which carries hands revolving behind an opaque face; another set of hands which revolve before the face and are therefore visible 20 from a position in front of the face are moved clockwise and counterclockwise at varying speeds, to produce an effect which appears ridiculous when contrasted with the operation of conventional clocks and therefore attracts the attention of on-lookers or passersby to the clock and to any display or advertising shown therewith. At intervals 25 which may be controlled either automatically or by observers, the eccentrically-operating hands may be caused to stop at positions corresponding 30 to the hands which are concealed by the opaque face, and thereby indicate the time of day.

One form of the invention is exemplified in the accompanying drawings and specification, but it should be understood that this disclosure 35 is intended not to limit the invention to any specific form, as the objects of the invention may be carried out in many different ways.

In the drawings—

Fig. 1 is a central vertical sectional view of a 40 novelty clock embodying the invention;

Fig. 2 is a front elevation, on a reduced scale, of the same clock;

Fig. 3 is an enlarged sectional view looking 45 on the line III—III of Fig. 1;

Fig. 4 is an enlarged view of a modified form of a portion of the mechanism illustrated in Fig. 1;

Fig. 5 is a diagrammatic illustration of the 50 electric circuits employed in the operation of the clock illustrated in Fig. 1;

Fig. 6 is an enlarged view of the portion of the 55 clock illustrated in Fig. 1 which supports and rotates the clock hands in an eccentric manner; and

Fig. 7 is a sectional view taken on the line VII—VII of Fig. 6.

As illustrated in the drawings, the invention is disclosed as contained by a casing 10, the front side of which may be closed by a transparent 5 glass window 11 held in position in any suitable manner, as by a threaded ring 12. Behind the glass 11 is a wall 13 which forms the face of the clock and which is preferably formed of non-transparent material such, for example, as glass 10 which has been colored or frosted to render it non-transparent. The wall 13 is provided with the usual numbers, as indicated in Fig. 2 of the drawings, so that it constitutes a clock face.

Within the housing 10 a conventional clock 15 mechanism not shown is contained by a casing indicated at 14. This clock mechanism may be of either an electrical or mechanical type, and is adapted to operate concentric shafts 15 and 16, which shafts correspond to those on an ordinary 20 clock which support and drive the hour-hand and minute-hand respectively. In the present case, the shafts 15 and 16 support and drive arms 17 and 18. For convenience, the arms 17 and 18 will be referred to as the "hour arm" and "minute 25 arm" respectively. The former carries an hour magnet 19 at one of its ends, and the latter carries a minute magnet 20 at one of its ends. The magnets 19 and 20 are counterbalanced by weights 21 carried at the opposite ends of the 30 arms 17 and 18. The magnets 19 and 20 are supported for rotation by their respective arms in a plane parallel to and directly behind the non-transparent face of the clock so that, although they are not visible from the exterior of the clock, 35 their positions will at all times designate the correct time of day.

Disposed in front of the wall 13 so that they overlap the clock face are the conventional hour-hand 22 and minute-hand 23. The hands 22 and 23 are driven by a mechanism generally indicated 40 at 24 in Fig. 1 and, presently to be described in detail, in a manner to cause them to rotate at varying speeds and in opposite directions with an action that is eccentric and designed to call attention to the operation of the clock. Each of the hands 22 and 23 carries a magnetically attractive member as indicated at 25 and 26 in Fig. 1, and which are counterbalanced by suitable weights 27 at the opposite ends of the hands. 45 The elements 25 and 26 are disposed at equal distances radially from the center of the clock face with the magnets 19 and 20, respectively, so that upon energization of the magnets 19 and 20 the elements 25 and 26 will be attracted to the 50 55

magnets, causing the hands to stop their erratic motion and come to rest in a position to indicate the proper time of day.

Figs. 1, 3, 6 and 7 illustrate the details of a suitable mechanism for imparting the normal eccentric operation to the hands 22 and 23. In these figures, a central bushing 38 is shown as connected to the wall 13 by means of a nut 31 and as supporting an upwardly extending bracket 32 and an inwardly extending bracket 33. The minute-hand 23, as best illustrated in Fig. 6, is supported by a square shaft 34 journaled at its inner end in a bearing 35 formed in the bracket 33. The hour-hand 22 is supported by a bushing 36 which is journaled in the bushing 38, the interior of the bushing 36 being hexagonal. Both the minute-hand and the hour-hand are rotated through a horizontally disposed driving disk 40 carried by a shaft 41 which is driven by an electric motor 42 which may include reduction gearing not shown to govern the speed of rotation of the disk 40.

In order that the constant rotary movement of the disk 40 may be transmitted to the minute-hand and hour-hand at variable speeds and periodically in opposite directions, the minute-hand shaft 34 is provided with a sliding drive 43 which includes a wheel 44 contacting the driving disk 40, and the hour-hand bushing 36 is provided with an internally fitted sliding drive member 45 provided with a wheel 46 contacting the driving disk 40. The drive members 43 and 45 are relatively rotatable, the member 43 serving as a bearing for the member 45, and are movable longitudinally with respect to the shafts which operate the hands 22 and 23. These drive members are locked against longitudinal movement with respect to each other by means of a nut 48 on the end of the inner member 43 which cooperates with a shoulder 49 on said inner member to prevent longitudinal movement thereon of the outer member 45.

Due to the construction just described, the driving members 43 and 45 may rotate independently of each other and may be moved longitudinally with respect to their common axis of rotation, but not with respect to each other. As the rotation of these driving members is imparted to them through their wheels 44 and 46 which engage the driving disk 40, it is apparent that any longitudinal movement will cause the driving wheels to move radially over the driving surface of the disk 40, thereby varying their speed of rotation and causing them to reverse their direction of rotation as they pass the center of the disk 40.

A bell crank 50 (see Fig. 3) which is pivotally supported by a bracket 51 has a bifurcated end which carries pins 52 engageable with a groove in the member 43 (see Fig. 6). The opposite end of this bell crank 50 is pivotally connected with a crank arm 54 which leads to an eccentric strap 55 surrounding an eccentric cam 56 secured to and driven by the shaft 41 of the motor 42. Consequently, rotation of the shaft 41 oscillates the bell crank and imparts a reciprocal movement to the drive members 43 and 45, causing their respective wheels 44 and 46 to move radially of the driving disk 40. In this manner the hands 22 and 23 are caused to move at varying speeds and alternately in opposite directions with no apparent reason and obviously with no relation to the correct time of day.

When the magnets 19 and 20 are energized, the hands 22 and 23 are brought to rest in positions

corresponding to the positions of the magnets, and the operation of the motor 42, which normally drives the hands 22 and 23, is interrupted in the manner illustrated in the wiring diagram shown in Fig. 5.

Referring now to Fig. 5, the magnets 19 and 20 are shown as energized from a suitable source of electric energy through lead wires 60 and 61. The wire 61 is grounded through the clock mechanism 14 and arms 17 and 18 to both of the magnets and the wire 60 leads to a pair of spring fingers 62 which engage collector rings 63 and 64 carried by the arms 17 and 18 and connected with the magnets 19 and 20, respectively, so that they may be continuously energized during the rotation of the arms. The wire 60 includes a switch 78 which is operated by a relay 71 in conjunction with a dashpot 72. The coil of the relay may be energized by closing a switch 73 which connects it with the main lines 60 and 61.

The switch 73, which is shown as a push-button, is illustrative of any type of switch that it may be desirable to use to close the circuit which causes the clock to tell the proper time. For example, if the clock is displayed in a window, the switch 73 may be of the type that is closed through the mechanism of a photo-sensitive cell so that any person stepping up to the window to view its operation will interrupt a light beam and cause the switch to be closed. As this and other types of switches that operate in novel manners are well-known, it is unnecessary that a further disclosure of the same be made herein.

Upon closing of the switch 73, the relay 71 is energized to raise its armature 74 and close the switch 76 against the resilient switch fingers 75. Connected with the upper end of the armature 74 is a plunger in the dashpot 72 which moves upwardly with comparatively little resistance, but which moves downwardly slowly, due to the fact that it must force the air or other fluid in the dashpot through a bleeder port 77, the opening to which is controlled by an adjusting screw 78. Thus, when the switch 73 is closed, it will remain closed for a period of time determined by adjustment of the screw 78 and sufficient to permit the successful operation of the clock.

The motor 42 is energized through conductors 80 and 81 connecting it with the main circuit, and the conductor 81 includes a relay switch 82 which is opened to de-energize the motor and permit the hands 22 and 23 to remain still when they have been attracted by the magnets 19 and 20. In order to accomplish this a relay 84, which, upon being energized opens the switch, is connected with the main circuit by conductors 85 and 86. The conductor 86 includes a switch which comprises a pair of rings 87 and 88 secured to the face and which may be electrically connected by contact members 89 and 90 on the hands 22 and 23. When the magnets draw the hands toward the face of the clock, these contact members engage the rings 87 and 88, and through the metallic bodies of the hands themselves, the rings are bridged to close the circuit to the relay 84, thereby opening the switch 82 and stopping the operation of the motor 42. Thus when the switch 73 is closed, the magnets 19 and 20 are energized, and as the hands 22 and 23 during their normal erratic motion pass these magnets, they come to a stop to indicate with respect to the face of the clock the proper time of day. Should one hand be stopped before the other, the motor 42 will continue to operate until the other hand registers with its magnet and stops. Dur-

ing the intervening moment, the driving wheel 44 or 46 of the hand which has been stopped will slide against the driving disk 40 rather than rotate therewith, and it is desirable that the pressure of the disk 40 be sufficiently light to permit this momentary sliding of either one wheel or the other. When both hands have come to rest, the motor and driving disk 40 will also stop.

It is apparent from the wiring diagram in Fig. 5 that some of the wires shown there, particularly those portions of the wire 86 which connect with the rings 87 and 88, must be disposed between the surface of the wall 13 and the rotating magnets 19 and 20. These wires may be very small and placed in close contact with the wall 13 to avoid being scraped by the magnets, but a preferred structure to avoid contact between such wires and the magnets is illustrated in Fig. 4 of the drawings wherein the wall 13 is shown as made of two spaced layers of glass or similar material so that the wires 86 may be disposed between these layers and thus will be protected from any possibility of contact by the magnets 19 and 20.

25 In operation, the face of the clock will appear as it is illustrated in Fig. 2 with the invisible arms 17 and 18 indicating the correct time and the visible hands 22 and 23 rotating until the switch is closed which compels the clock to tell the time. The hand 22 is then stopped by the magnet 19, and the hand 23 is stopped by the magnet 20, and both hands will remain in this position until the switch is again opened by the mechanism described above.

35 The clock as described above gives the correct time in any given time zone, but the earth's surface is divided into twenty-four time zones and it is sometimes desirable to know the time in one or more of the other zones. By substituting for the magnets 19 and 20 complete circles of magnets, each circle containing twenty-four equally spaced magnets, the correct time in any one of the earth's time zones could be given by the single clock. The magnets would of course be energized in pairs by twenty-four separate circuits controlled by the same number of switches corresponding to the switch 13 and each labeled to indicate the zone controlled by it.

While but a single form of the invention is described and shown herein, it is of course to be understood that many changes may be resorted

to in the construction and arrangement of the parts thereof within the scope of the appended claims.

Having thus described our invention, what we claim and desire to secure by Letters Patent is—

1. A clock comprising a pair of hands rotatable before a face, means normally effecting erratic operation of said hands, a clock mechanism concealed behind the face and normally operating independently of said hands, and means operable to effect control of the hands by said mechanism. 10

2. A clock comprising a pair of hands rotatable before a clock face, drive means for continuously rotating said hands without reference to the time of day, a clock mechanism concealed behind said face, and means operable to effect control of the hands by the clock mechanism. 15

3. A novelty clock comprising a clock face, a clock mechanism, a pair of magnets moved by said clock mechanism in circular paths behind 20 the face in the manner of the hands of a clock, a pair of hands carrying magnetic material rotatable in front of the clock face, and means for energizing said magnets to cause said hands to be attracted by them to indicate the time of day. 25

4. A novelty clock comprising a clock face, a clock mechanism, a pair of magnets supported and moved by said clock mechanism in circular paths behind said face, a pair of hands carrying magnetic material disposed in front of the face, 30 a motor and means for driving said hands in an erratic manner by said motor, and means for energizing said magnets and stopping said motor to cause the hands to be attracted by the magnets and to be stopped in positions telling the correct 35 time of day.

5. A clock of the character described comprising a clock mechanism, a pair of arms driven by said mechanism and corresponding to the minute-hand and hour-hand of a conventional clock, 40 an electromagnet carried by each arm and rotatable thereby, a clock face concealing said mechanism and magnets, a pair of hands rotatable in front of said face, a motor normally driving said hands without reference to the time, means for energizing said magnets whereby they will cause the hands to stop in positions indicating the correct time, and means operable upon stopping of the hands to de-energize said motor. 45
